UNITED STATES PATENT OFFICE.

GEORGE DUNHAM, OF UNIONVILLE, CONNECTICUT.

NUT-MAKING MACHINE.

SPECIFICATION forming part of Letters Patent No. 436,172, dated September 9, 1890.

Application filed October 14, 1889. Serial No. 326,975. (No model.)

To all whom it may concern:

Be it known that I, GEORGE DUNHAM, a citizen of the United States, residing at Unionville, in the county of Hartford and State of Connecticut, have invented certain new and useful Improvements in Nut-Making Machines, of which the following is a specification.

My invention relates to improvements in nut-making machines; and the objects of my improvements are to improve the efficiency of the machine in many respects, and particularly to improve the construction of the blanking-out and central-hole punching devices, the flattener, the scrap-clearers, and to arrange the feed or transfer underneath the gages.

In the accompanying drawings, Figure 1 is a front elevation of my machine. Fig. 2 is a side elevation thereof. Fig. 3 is an enlarged horizontal section on line *xx* of Fig. 1. Fig. 4 is a like view of a portion of the same with some of the parts removed. Fig. 5 is a vertical section of a portion of my machine on line *yy* of Fig. 3. Fig. 6 is a vertical section of the central-hole, blanking-out, and crowning dies on line *zz* of Fig. 3, together with a side elevation of the punches belonging to said dies. Fig. 7 is a vertical section through the trimming-die on line *ww* of Fig. 3. Fig. 8 is a side elevation still further enlarged, showing one end of the blanking-die holder and the gages attached thereto. Fig. 9 is a vertical section corresponding with Fig. 5, but showing a modification in the flattener and gages. Fig. 10 is a side elevation showing the modified form of said flattener. Fig. 11 is a partial horizontal section and partial plan view of detached parts, showing, on a larger scale, the spring-pressed gages through which the bar is fed to the blanking-die; and Fig. 12 is a vertical section of detached parts on the line *ww* of Fig. 3 on a larger scale than that for Fig. 7.

A designates the frame of the machine, which is similar to that of a power-press, and at the upper end of which is the crank-shaft B for driving the punch-slide C in the usual manner of such machines. Said crank-shaft also carries the cams D D and E for driving, respectively, the slides 11 11 and 12. The cams D D and slides 11 11 act upon the roller 13 for reciprocating the carriage F in the man-

ner shown and described in my patent of January 24, 1888, No. 376,769, for a mechanical movement. This carriage F is provided with a finger-slide G, which moves from front to rear in addition to its lateral movement with the carrier F. The inner end of this slide is provided with a carrying-finger 14 and a scrap-clearer 15, Fig. 4. This finger-slide is actuated by means of the grooved cam E on the crank-shaft B, the vertically-moving slide 12 connected therewith, rocking arm 16 on the rock-shaft 17, one end being secured to the slide 12, and the second rocking arm 18 at the front of the machine, which projects upwardly from said rock-shaft 17 to a pin 19 on the front end of the finger-slide G, said rocking arm being slotted vertically at a point where said pin passes through it. This finger-slide and the means for operating it are substantially the same as corresponding parts of the machine for finishing nuts shown and described in my application, Serial No., 304,694, filed March 25, 1889, and of themselves form no part of the present invention. This mechanism imparts to the finger-slide what is often termed a "four-motion" movement. Some of the other features shown and described in said application are wholly or partially shown in the drawings, and may be embodied in the machine of the present application, but of course are not of the present invention, excepting as they may enter into new combinations.

The punch-slide C is provided with a central-hole punch 20, Fig. 6, the blanking-out punch 21, the flattening-punch or hammer 22, and the trimming-punch 23. The central-hole punch 20 is in the rear of the blanking-out punch 21, while the punches 22 and 23 are at one side of said blanking-out punch in a line at right angles to a line running through the center of the punches 20 and 21.

H designates the die-bed, to which the several dies and gages are secured.

24 designates a die-holder for the crowning-die 25, which holder is secured to the die-bed.

26 designates the die-holder for the flattening die or anvil 27 and the trimming-die 28. On the top of the crowning-die holder 24 is another die-holder 29, bearing the central-hole die 30, and still another holder 34, bearing the blanking-out die 35 and flattener 36, the position of the several dies corresponding with

the several punches before described, while the crowning-die is immediately under the blanking-out punch and die. The rod or bar is fed in between the spring-pressed 5 gages 31 31 and under the take-off or picker 32. Said spring-gages are in substance substantially the same as patented to me in my patent of October 30, 1888, No. 391,951, for a nut-making machine. The under side of the 10 take-off or cap 32 is recessed from front to rear through its middle portion to make room for the spring-pressed gages 31 and the space between them through which to feed the bar. These gages 31 are pivoted to the top of the 15 die-holder 29, as shown in Fig. 11, in which figure 60 designates their pivot-pin. The rear ends of said gages 31 are provided with upwardly-projecting lugs 61, through which lugs the bodies of the screws 62 pass. At the 20 rear edge of the take-off there is a bracket 63, into which the threaded ends of these screws enter. A spring 64 is secured by a set-screw 65 to said bracket 63, the ends of which spring bear upon the upwardly-projecting 25 lugs 61 of the gages 31 with a constant tendency to throw apart the rear ends of said gages, thereby pressing their front ends toward each other. The screws 62 may be turned out or in to limit the extent of inward 30 movement of the front ends of said gages. That side of the blanking-out punch 21 which faces the central-hole punch 20 is recessed or cut away, as at 33, Fig. 6, and the central-hole punch 20 is shorter than the blanking- 35 punch, so that its end is in the same plane as said cut-away portion. This blanking-punch may be formed solid in one piece or its lower end may be a separate piece dovetailed in, as shown in Fig. 6. At the front of the 40 blanking-out die 35 there is a stop or gage 47. The flattener 36 is a loose block which plays slightly up and down in the blanking-die holder 34, the same being forced downward to flatten the blank by means of the flattening-punch or hammer 22. A lateral passage 45 is left for the nuts through the machine underneath the blanking-out die 35, flattener 36, and above the crowning-die 25, flattening-die 27, and trimming-die 28. On the front 50 and rear sides of this passage-way through the blanking-out-die holder I arrange two spring-gages 37 37, the same being secured to said holder 34 by means of screws 38, Fig. 8, that pass through slots in the shank of said gages, 55 whereby the same may be adjusted to or from the front of the machine.

While I prefer to employ two yielding gages 37, if desired, a fixed gage might be substituted for one of said yielding gages. These 60 gages extend from the crowning and blanking-out dies to a point near the flattening-die, as shown. I also employ a rear gage 39 and a front gage 40 for gaging the opposite edges of the nut, which gages in the preferred form 65 extend from a point near the crowning-die along by the sides of the flattening and trimming dies, and I prefer to mount these gages

upon yielding slides 41 41, substantially such as are shown and described in my aforesaid application, Serial No. 304,694. The manner 70 of applying the spring to these slides is shown in Fig. 12, in which the slide 41 is shown as provided with a downwardly-extending lug 66, through which a set-screw 67 passes with its end resting against the block or piece 70, 75 over which said slide moves. Another screw 68 passes loosely through said lug 66, and its threaded end is screwed into said block or piece 70 or other stationary part, and a spiral spring 69 is placed on said screw with one end 80 bearing on the screw-head and its other end on said lug, whereby said spring always has a tendency to press the slide forward until it is stopped by the end of the set-screw. By turning said set-screw 67 the limit of the forward movement of the slide may be adjusted as desired. I also provide a sliding side gage 42 and a latch-gage 43 in the vicinity of the trimming-die for stopping and holding the nut in the manner hereinafter described. 85 The body of the latch-gage is so thin as to constitute a spring, and it is in the form of an angle-lever, as shown in Fig. 3, so as to be out of the way of the trimming-punch. The under side of its shorter arm is beveled, as 90 shown in Fig. 5. The side gage 42 should slide longitudinally and be forced toward the latch-gage by a suitable spring, as, for instance the spring 48, Fig. 3. The front and rear gages are preferably made light and thin and set a little 95 distance above the respective dies. In any event the front gage is left above said dies a distance sufficient to allow room for the carrying-finger 14 and scrap-finger 15 to pass in under said gage. The carriage F is provided with 100 a rearwardly-projecting arm, which carries the pushing-finger 44, which finger is in the line of the transverse passage-way through the blanking-out-die holder 34. Within the crowning-die is the ordinary knockout 49, 105 that is forced upwardly by the lever 50, intermediate said knockout and the lower end of the vertical slide 12.

Instead of making the front and rear gages extend along by the front and rear sides of the flattening-die 27, the flattener 36 may be provided with front and rear side ledges 45, as shown in Figs. 9 and 10, to take the place of a portion of said front and rear gages, which are made correspondingly shorter. The flattener is provided with a steady pin or spline 46 to prevent it from rotating within the holder, in which it is mounted. The corner at the under side of the flattener which is nearest the crowning-die is beveled off a little, so that 115 the flattener may be pushed upward when a nut is forced under it.

In the construction shown in Figs. 9 and 10 the flattener is held up by the peripheral shoulder, and in the construction first described it may rest upon the front and rear gages, which will act as springs to hold it up when not depressed by the flattening-punch. 120 A bar of metal of the proper width is fed 125 130

into the machine and stopped at the proper point, when the punch-slide descends to punch the central hole in the bar. The bar is then fed along the distance of one nut and another hole punched, and finally to a point in under the blanking-die 35, which cuts off a proper length for a nut-blank. After one piece or nut-blank has been cut from the end of the bar by the blanking-out punch and die the end of the bar is stopped against the stop-gage 47, and a hole in the bar is punched and a nut-blank cut off at each stroke of the press. The punch 21 by the continued motion of the punch-slide also forces the nut-blank down between the gages 37 37 and upon the crowning-die to crown or round one face of the nut. Said gages hold the blank in proper position as it passes to the crowning-die, and also hold it after it has been crowned to prevent it from following the punch on its return. The punching of the central hole is done substantially simultaneous with the crowning of the nut, and the blanking-out or shearing operation takes place a little prior in the movement of the press-slide to the act of punching the central hole. In punching said hole the bar is inclined to lengthen somewhat, and by making the cut-away portion 33 in the blanking-punch immediately opposite the end of the central-hole punch I avoid crowding of the metal between the punches 20 and 21 in punching the central hole. When the punch 21 rises again, the punch 20 is withdrawn from the bar, so that the bar readily yields and gets out of the way of the larger lower end of the punch without creating any undue friction. When these operations of punching the central hole, blanking out, and crowning the nut are performed, the carriage F is at the right-hand end of its stroke and the finger-slide G is drawn toward the front away from the dies 27 and 28. After said punching operations the cam E on the crank-shaft B moves the slide 12 downward and raises the knockout 49 to loosen the nut from the crowning-die. The mechanism intermediate said slide 12 and finger-slide G operates to throw said slide forward. The carriage F then moves to the left, when the pushing-finger 44 engages the nut lying between the gages 37 37 and carries said nut from the crowning-die 25 to its position over the flattening-die 27, and when the carriage is at its left-hand end of its stroke the finger-slide G is withdrawn by moving toward the front. The punch-slide again descends, when the flattening-punch 22 strikes the top of the flattener 36 and forces it down upon the nut to flatten it. The flattener forms a covering for the passage-way for the nuts and prevents the nuts from following the upward movement of the flattening-punch. It is also best to have the nut lift the flattener a little as it passes under the same, so that the flattener will serve to arrest the nut over the flattening-die and hold it squarely down on said die prior to the nut re-

ceiving any pressure from the flattening-punch. Upon the ascent of the punch-slide the carrier and finger-slide move as before described, when the carrying-finger 14 is brought into position by the right-hand side of the nut on the flattening-die 27, and as the carriage moves to the left the nut is carried to the trimming-die 28. The carriage may move far enough to carry the nut a little beyond its proper position over the trimming-die, the sliding side gage 42 yielding to permit the nut to pass thus far. In passing the latch-gage said gage springs upwardly and lets the nut pass and then springs downwardly again into position. Upon the withdrawal of the finger-slide the sliding side gage presses the nut back against the latch-gage to hold the nut by two sides, while the front and rear gages hold it by the other two sides. The punch-slide and punch 23 then descend and force the nut into the trimming-die to trim it, from which die it may fall through a proper opening to any suitable receptacle. At the next repetition of the same movements the scrap-clearer 15 on the finger-slide G, in advance of the finger 14, will brush or push away all of the scrap from the trimming-die to make it ready for the succeeding nut.

I have specifically followed only one nut through the machine; but after the machine is started all of the several operations described will be performed at their respective places at every reciprocation of the press-slide.

By having the carrying-finger work under the front gage I am enabled to attach the scrap-clearer to the finger-slide, and I can also have a portion of the side gages formed on the flattener or have the gages otherwise supported in position from above.

The several gages that bear upon the nut in its passage laterally through the machine, especially the gages 37, also perform the function of holders, or, in other words, they gage by holding the nut.

I claim as my invention--

1. The combination of a central-hole punch and die and a blanking-out or shear punch and die, the blanking-out or shear punch having the cut-away or reduced portion above its cutting end on that side which faces the central-hole punch, substantially as described, and for the purpose specified.

2. A blanking-out or shear die holder having a lateral passage-way under the die, in combination with a yielding gage or holder within said passage for acting on the edge of the nut-blank, and a pushing-finger to force said nut-blank along, substantially as described, and for the purpose specified.

3. The combination of a blanking-out or shear die holder having a lateral passage-way for the nut-blank, the blanking out punch and die, the crowning-die under said blanking-out die within said passage-way, a yielding gage or holder also within said passage-way and between the blanking-out and crowning-

- dies, and a pushing-finger to force the nut-blank along, substantially as described, and for the purpose specified. 50
4. The combination of the flattener-die, the flattener-punch, and a separate flattener intermediate said die and punch, substantially as described, and for the purpose specified. 55
5. The combination of the flattener-die, flattener-punch, front and rear gages by the sides of said flattener-die, and the flattener interposed between said flattener die and punch and covering the space between said gages, substantially as described, and for the purpose specified. 60
15. 6. The blanking-out or shear die holder and the flattener 36 mounted therein over a bed, substantially as described, and for the purpose specified. 65
7. The blanking-out or shear die holder having the lateral passage-way for the nuts, the flattener 36, mounted in said holder over said passage-way, and gages for the front and rear sides of said passage-way, substantially as described, and for the purpose specified. 70
25. 8. The combination of the flattener die and punch, the flattener, front and rear gages, and the trimming die and punch, substantially as described, and for the purpose specified. 75
9. The combination of the crowning die and punch, the flattener die and punch, the flattener, and the trimming die and punch, substantially as described, and for the purpose specified. 80
35. 10. The combination of the crowning die and punch, the flattener die and punch, the flattener, the trimming die and punch, and gages, substantially as described, and for the purpose specified. 85
40. 11. The combination of the blanking-out die and punch, the crowning-die, the flattener die and punch, the flattener, and a trimming die and punch, substantially as described, and for the purpose specified. 90
45. 12. The combination of a blanking die and punch, a crowning-die, flattening devices, and a trimming die and punch arranged for successively blanking, crowning, flattening, and trimming a nut-blank in the order named, 95
- substantially as described, and for the purpose specified. 50
13. The combination of a trimming die and punch, front and rear gages, and gages at the right and left, substantially as described, and for the purpose specified. 55
14. The combination of a carrier, rear and front gages 39 and 40, the sliding gage 42, and latch-gage 43, said gages acting to hold a nut on four sides, substantially as described, and for the purpose specified. 60
15. The combination of dies and punches for operating upon a nut-blank, the elevated front gage, and a carrier-finger working under said front gage and over said dies, substantially as described, and for the purpose specified. 65
16. The combination of a carrier, mechanism for operating said carrier with a four-motion movement, and a scrap-clearer mounted on said carrier to move in advance of the nut, substantially as described, and for the purpose specified. 70
17. In a nut-machine, the finger-slide having the carrying-finger 14, and rigidly connected therewith the scrap-clearer 15 with a space between them for the nut, substantially as described, and for the purpose specified. 75
18. The combination of the crowning die and punch, flattening devices, the trimming die and punch, the reciprocating carriage F, the pushing-finger 44 on said carriage, the finger-slide moving with said carriage and also at right angles to its movement, and the carrier-finger and scrap-clearer mounted on said finger-slide, substantially as described, and for the purpose specified. 80
19. The combination of the flattener die and punch, the flattener held over said die, a front gage also elevated above said die, and a carrier-finger working underneath said front gage and flattener, substantially as described, and for the purpose specified. 85
